UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed January 4, 1926. Serial No. 79,093.

This invention relates to car roofs of the flexible outside metal type wherein light gage roofing sheets extend from eaves to ridge of the car and are loosely secured to the car and to each other in a manner adapted to permit relative movement of the sheets to a limited extent so as to be able to accommodate themselves to the distortions of the car frame.

10 The principal object of the present invention is an improved ridge seam construction that will secure an oscillatory movement of the sheets near the middle portions of their ridge ends whenever there is movement of the sheets. Other objects are to simplify 15 the operation of forming the ridge seam covers and thereby reduce the cost thereof, to increase the strength and rigidity of said covers and to effect greater economy of material.

The invention consists principally in the shape and arrangement of the cooperating portions of the ridge seam covers and roof sheets; and it also consists in the parts and 25 in the arrangements and combinations of parts hereinafter described and claimed.

In the accompanying drawing, which forms part of this specification and wherein like symbols refer to like parts wherever 30 they occur,

Fig. 1 is a plan view of a portion of a flexible outside metal car roof embodying my invention, portions of the roof being shown broken away to more clearly illustrate 35 the invention;

Fig. 2 is a vertical transverse section through a transverse seam on the line 2-2 in Fig. 1;

Fig. 3 is a vertical cross-section through 40 the eaves portion of the car on the line 3-3 in Fig. 1;

Fig. 4 is a vertical cross-section through 45 the ridge portion of the roof midway of adjacent transverse seams on the line 4-4 in Fig. 1;

Figs. 5 and 6 are similar cross-sectional views on the lines 4-4 and 5-5, respectively, in Fig. 1;

Fig. 7 is a side elevation of the ridge seam 50 cover; and

Fig. 8 is an end view of the ridge end of a sheet.

Referring to the accompanying drawing, my invention is shown applied to a car having 55 a wooden sheathing consisting of roof sheath-

ing boards 10 supported on side plates 11 and a ridge pole 12. Metal roof sheets 13 are arranged on the roof sheathing boards side by side in two rows on opposite sides of the ridge, the two rows of roof sheets being spaced apart at the ridge and the sheets in each row being spaced apart at their sides. The roof sheets on opposite sides of the ridge are arranged in alignment transversely of the car; and mullions or battens 60 14 are secured to the car in the spaces between the side margins of the sheets. These mullions extend transversely of the car from eaves to eaves thereof and are of less width than the spaces between the side margins 65 of the sheets to permit limited angular movement of the sheets therebetween.

The ridge and side margins of the roof sheets are turned up and are thence bent inwardly over the body portions of the sheets 70 and thence downwardly to form upstanding ridge and side seam flanges or hollow ribs 15 and 16 of substantially C-shaped cross-section. The eaves ends of the roof sheets are doubled-under to form hook flanges 17 75 that loosely engage the doubled-over hook flanges of angle flashing strips 18 secured to the eaves of the car, such arrangement serving to loosely secure the sheets to the 80 car at the eaves.

The adjacent side seam flanges 16 of the sheets, together with the mullions or battens located therebetween, are covered by inverted channel-shaped transverse or side seam covers or caps 19 that extend from 85 eaves to ridge and rest on said battens. The side walls of the seam covers 19 have inwardly and upwardly extending hook flanges 20 that interlock with the side seam flanges 16 of the sheets. The eaves ends of 90 the transverse seam covers 19 are loosely held in position at the eaves by extensions 21 that are turned down over the eaves ends of the mullions and are thence turned under the doubled-under corners of the roof 95 sheets and the doubled-back flanges of the eaves flashing strips.

Pressed metal ridge seam covers or caps 22 of substantially inverted channel-shaped 100 section straddle the spaced ridge flanges 16 of adjacent sheets and have outstanding base flanges 23 that rest on the body portions of said sheets inside the ridge flanges thereof. The adjacent ends of the ridge seam covers 22 and the transverse or side 105 110

seam covers 19 are held in position on the car by means of the usual pan-shaped four-way center or corner caps 24 that are secured in position by means of bolts 25, which serve also to secure the running board saddles (not shown) in position.

The inverted channel-shaped ridge seam covers 22 are narrowest at the middle and gradually increase in width towards each end. The surplus metal resulting from the decreased width of the middle portions of the ridge seam covers is pressed up, on opposite sides of their longitudinal center lines, to form two laterally spaced longitudinally extending hollow ribs or inverted channels or grooves 26. These ribs 26 are narrowest and deepest at the transverse center line of the ridge seam covers and gradually increase in width and decrease in depth towards the ends of said covers where they merge into the plane of the tops thereof. Thus, the cross-sectional shape of said seam covers changes gradually from a single inverted channel at each end to a section at the middle comprising two laterally spaced inverted channels. As shown in the drawing, the ridge seam covers, together with the ribs or grooves thereon, are made widest at the ends by curving their opposite side walls in opposite directions away from each other; but it is noted that this widening or flaring of said ridge seam covers and said ribs may also be produced with straight side walls that diverge from each other from the middle of the covers towards their ends.

The ridge seam flanges 15 of the roof sheets are of a width corresponding substantially to the width of the narrow middle portions of the downwardly opening longitudinal grooves formed by the hollow ribs 26 on the tops of the ridge seam covers, and said ridge flanges have a maximum height midway of their ends and gradually decrease in height towards the side flanges of the sheets, the tops of the ridge flanges being pitched at substantially the same inclination as the tops of said hollow ribs.

By the arrangement described, the hollow ribs of the ridge seam covers are adapted to closely embrace the ridge seam flanges of oppositely disposed roof sheets at the middle of the ridge ends thereof and thus maintain a proper spacing of the ridge ends of said sheets as well as preventing independent or joint bodily movement thereof cross-wise of the car. By reason of the double convexity of the side walls of the grooves formed by the ribs, said seam caps closely embrace the ridge flanges of the roof sheets at the middle of the ridge ends and are spaced therefrom at the sides of the sheets, whereby said sheets are forced to rock or roll about the contacting portions of the ridge seam covers during the racking

and weaving of the car frame and thus accommodate themselves to the distortions thereof.

The principal advantages of the foregoing construction is that it locates the surfaces, about which the sheets roll or rock, in the main body portion of the seam covers, thereby adapting said covers to be pressed by a single pressing operation and without injury to the metal; it greatly increases the strength and rigidity of the seam covers and thus prevents said covers from becoming bent, twisted or crushed and interfering with or preventing the desired sluing movement of the sheets; and it is of simple and compact design and can be produced with great economy.

What I claim is:

1. A flexible car roof comprising movably mounted roof sheets spaced apart along their adjacent margins and having raised portions extending along said margins, and a seam cover secured to the car and covering the raised portions of adjacent sheets, said seam cover having side walls that contact with the inner sides of said raised portions for a portion of their length only, and having a portion of its top extending between and contacting with the outer sides of said raised portions for a portion of their length only.

2. A flexible car roof comprising movably mounted roof sheets spaced apart along their adjacent margins and having raised portions extending along said margins, and a seam cover secured to the car and covering the raised portions of adjacent sheets, said seam cover being provided with downwardly opening longitudinal grooves that straddle said raised portion and have contact with both sides thereof for a portion of their length only, said grooves being formed in the top of said seam cover.

3. A flexible car roof comprising movably mounted roof sheets spaced apart along their adjacent margins and having raised portions extending along said margins, and a seam cover secured to the car and covering the raised portions of adjacent sheets, the top of said seam cover being provided with downwardly opening longitudinal grooves that closely embrace both sides of said raised portions midway of their length and are normally spaced therefrom at their ends.

4. A flexible car roof comprising movably mounted roof sheets spaced apart along their adjacent margins and having hollow ribs extending lengthwise thereof, and a seam cover secured to the car and covering said ribs, said seam cover being wider at its ends than at its middle and changing from an inverted channel-shaped section at each end to a section at the middle comprising two laterally spaced inverted channels whose sides closely embrace said ribs substantially midway of their length.

5. A flexible car roof comprising movably mounted roof sheets spaced apart along their adjacent margins and having upstanding seam flanges extending lengthwise thereof, and a seam cover secured to the car and covering said upstanding seam flanges, said seam cover being of substantially inverted channel-shaped section and having hollow laterally spaced longitudinal ribs in its top 10 that are deepest and narrowest at the middle portion of the seam cover and gradually decrease in depth and increase in width towards its ends where they merge into the plane of the top of said cover, said ribs straddling said seam flanges whose top portions slope downwardly from their middle towards their ends to correspond substantially to the slope of said ribs. 15
6. A flexible car roof comprising movably mounted roof sheets spaced apart along their adjacent margins and having upstanding seam flanges extending lengthwise thereof that have a maximum depth at their middle and gradually decrease in depth to their 20 ends, and a seam cover covering the seam flanges at the adjacent margins of said sheets, said seam cover having a minimum width at its middle and gradually increasing in width at its ends, said seam cover 25 having longitudinal laterally spaced channels in its top that fit over the adjacent seam flanges, said channels being narrowest and deepest at the middle of said seam cover and gradually increasing in width and increasing 30 in depth toward the ends thereof. 35
7. A seam cover for a car roof, said seam cover gradually changing from a substan-
- tially inverted channel-shaped section at each end to a section at its middle comprising two laterally spaced inverted channels. 40
8. A seam cover for a car roof, said seam cover being of substantially channel-shaped section and having hollow longitudinal ribs formed in its top portion that are narrowest 45 at the middle of said seam cover and widen towards each end thereof.
9. A seam cover for a car roof, said seam cover being of substantially channel-shaped section and having hollow longitudinal ribs formed in its top portion that are narrowest 50 at the middle of said seam cover and widen towards each end thereof, said ribs having a maximum depth at the middle of said seam cover and merging into the top thereof adjacent to its ends. 55
10. A seam cover for a car roof, said seam cover comprising a member of substantially inverted channel-shaped section, said member being of greater width at its ends than at its middle, and having laterally spaced 60 longitudinally extending hollow ribs in its top that are narrowest at the middle of said seam cover. 65
11. A seam cover for a car roof, said seam cover comprising an inverted channel-shaped member of greater width at its ends than at its middle and having laterally spaced hollow ribs in its top that gradually increase in width and decrease in depth from the middle of said seam cover towards the 70 ends thereof.

Signed at New Kensington, Pa., this 29th day of December, 1925.

CHARLES DAVID BONSALL.
